UNITED STATES PATENT OFFICE.

EDMOND A. FORDYCE, OF BOSTON, MASSACHUSETTS, ASSIGNOR, BY MESNE ASSIGNMENTS, TO LAMSON CONSOLIDATED STORE SERVICE COMPANY, OF NEWARK, NEW JERSEY, A CORPORATION OF NEW JERSEY.

PNEUMATIC-DESPATCH-TUBE APPARATUS.

SPECIFICATION forming part of Letters Patent No. 777,723, dated December 20, 1904.

Application filed August 25, 1904. Serial No. 222,087.

To all whom it may concern:

Be it known that I, EDMOND A. FORDYCE, of Boston, in the county of Suffolk and State of Massachusetts, have invented certain new and 5 useful Improvements in Pneumatic-Despatch-Tube Apparatus, of which the following is a specification.

My invention relates to improvements in pneumatic-despatch-tube apparatus; and its 10 object is to devise an apparatus on the vacuum principle which is economical and effective and through which no air passes when the apparatus is not in use.

My invention consists in certain novel features hereinafter described, and particularly 15 pointed out in the claims.

In the accompanying drawings, which illustrate a construction embodying my invention, Figure 1 is a side elevation, partly in section, 20 with parts in their normal positions and not in use. Fig. 2 is a similar view showing the position of the parts after a carrier has been introduced for transit to the central station from one of the substations. Fig. 3 is a similar view showing the position of the parts 25 upon the introduction of a carrier at the central station for transit to a substation.

Like letters of reference refer to like parts throughout the several views.

30 A represents a transit-tube secured to one end in the terminal A' at a substation and at the opposite end to the terminal A² at the central station. At the terminal A' the tube A is slotted at A³, and at the terminal A² the tube A is provided with a series of slots C', which allow communication between the tube A and the terminal A' A². The upper end of the transmission-tube A at the substation is closed by the valve B, and its opposite end at 35 the central station is closed by the valve C, as shown. The terminal A² is connected by the pipe D to the chamber E, and this chamber E communicates, by means of the tube E', with a suitable exhauster or pump. The upper end of the tube E' is normally closed by the valve E², pivoted at E³, and said valve is provided with the rigid arm E⁴, to which is pivotally connected the rod E⁵, secured to the

piston-rod F, working in the cylinder F². The exhaust-tube E' is connected to the upper part of the cylinder F² by the pipe G and to the lower part of the cylinder F² by the pipe G'. This pipe G' has a valve G², the purpose of which will be hereinafter explained. At the substation there is located 50 in an offset B' the valve B² and pivoted therein at B³ and with its outer end closing the pipe H, which extends from the substation to the central station and is connected by the pipe H' to the under side of the cylinder F². 55 The end of the pipe H at the central station is closed by the valve J, which is suitably pivoted on the support J' and has its inner end extending into the carrier transit-tube K.

With the parts in the position shown in Fig. 60 1, the exhaust from the cylinder F² through the pipes G and G' being equal, the piston F drops by gravity to its lower position, as shown, and remains in this position when the apparatus is not in operation and in such position closes the valve E², so that the exhaust does not take place through the transit-tubes, 65 and at the same time there is a vacuum created in the pipes H and H' through the pipe G', connected to the exhaust-tube E', which 70 is connected to the exhauster, so that an exhauster is created in the pipes H H' through the lower part of the cylinder F², through the pipe G', into the pipe E', and thence to the exhauster. When a carrier is to be sent from 75 a substation to the central station, Fig. 2, the valve B is raised and the carrier (which is marked X) is introduced and in its descent strikes the inner end of the valve B², which 80 opens the upper end of the pipe H, which normally is under the vacuum by the pipes G' and H'. With this valve open atmospheric pressure enters the pipe H and passes along the pipe and through the pipe H' to the bottom of the cylinder F² and raises the piston 85 F', and with it the valve E², (see Fig. 2,) so that the exhaust-tube E' is in communication, 90 through the chamber E and terminal A², with the transit-tube A, terminal A', and transit-tube K, exhausting the air from in front of 95 the carrier, which is driven by the atmos-

pheric pressure behind it through the transit-tube A and striking the valve C opens the same and passes around the chute C² and is discharged into a suitable receptacle. After 5 the carrier has passed the valve B² said valve closes the upper end of the pipe H, and thus cuts off the atmospheric pressure from acting through the pipe H' on the bottom of the piston F', and as the suction on the tube and bottom 10 tom of said piston F' through the pipes G and G' is equal the piston F' gradually drops from its upper position (shown in Fig. 2) to the lower position, (shown in Fig. 1,) and in returning to its lower position it closes the valve E², which when closed cuts off the exhaust through the transit-tube A and the parts assume their normal position. (Shown in Fig. 1.) By this arrangement no air passes through 15 the transit-tube except when a carrier is in transit from a substation to the central station.

The pipe G' is provided with a valve G² for the purpose of regulating the descent of the piston F', and in short lines this valve would be wide open, so that the piston F' would drop 20 quickly, while in long lines the valve G² would be nearly closed, so that the fall of the piston F' would be slow in both cases, allowing for the discharge of a carrier before the valve E² is closed and the vacuum cut off.

30 When a carrier is to be sent from the central station to a substation, it is inserted into the top of the tube K with the parts in the position shown in Fig. 1 and, descending, strikes the inner end of the valve J, Fig. 3, which opens the pipe H to atmospheric pressure, which passes down through the pipe H and through the pipe H' into the cylinder F², and the piston F' being in the position shown 35 in Fig. 1, with the vacuum on both sides 40 equal, the said atmospheric pressure forces the piston F' into the position shown in Fig. 3, thereby opening the valve E² in the position shown in Fig. 2 in the manner previously described, and the exhauster connected to the 45 tube E' draws the air through the tube E', terminal A², transit-tube A and its slots A³, terminal A', and pipe K through its slots A⁴, and the atmospheric pressure behind the carrier forces it through the pipe K and opening 50 the valve K' passes to the chute K² and from said chute to a suitable receptacle. The operation in both directions is identical, and no air is drawn through either tube except when a carrier is in transit, and, further, 55 these tubes are entirely independent both in forwarding and returning. When a carrier or carriers are in transit through the tubes, a carrier or carriers can also be in transit through the tube K and all will be delivered, 60 as the piston F' will not drop to the bottom of the cylinder F² until the last carrier has been discharged, the reason being that the valve E² opens every time a carrier is introduced into either the tube A or the tube K.

65 Consequently the atmospheric pressure enter-

ing keeps the piston F' up to the top of the cylinder F² until the introduction of carriers is stopped, when said piston F' drops to its normal position in the cylinder F².

The valves B² and J are counterweighted, 70 so that their outer ends normally close the upper openings of the pipe H.

I do not limit myself to the arrangement and construction shown, as the same may be varied without departing from the spirit of my 75 invention.

Having thus described the nature of my invention and set forth a construction embodying the same, what I claim as new, and desire to secure by Letters Patent of the United 80 States, is—

1. In an apparatus of the character described, a transit-tube through which carriers are transmitted, an air-valve controlling the passage of air through said tube and normally 85 closed, an exhaust-tube, mechanism under the control of said exhaust-tube for operating said valve and mechanism operated by the insertion of a carrier into said tube for opening said air-valve and allowing a passage of 90 air through said tube for driving carriers.

2. In an apparatus of the character described, a transit-tube through which carriers are transmitted, an air-valve controlling the passage of air through said tube and normally 95 closed, an exhaust-tube, mechanism under the control of said exhaust-tube and normally holding said air-valve closed, and mechanism operated by the insertion of a carrier for opening said air-valve to allow a passage of 100 air through said transit-tube.

3. In an apparatus of the character described, a transit-tube through which carriers are transmitted, an air-valve controlling the passage of air through said tube and normally 105 closed, an exhaust-tube, mechanism under the control of said exhaust-tube for operating said valve, mechanism operated by the carrier upon its insertion into the transit-tube for opening said air-valve, and mechanism for closing said 110 air-valve after the insertion of the carrier.

4. In an apparatus of the character described, a transit-tube through which carriers are transmitted, an air-valve for controlling the passage of air through said transit-tube 115 and normally closed, an exhaust-tube, communication between said exhaust-tube and said transit-tube and normally closed by said valve, a cylinder, a piston in said cylinder, connections between said cylinder and said 120 exhaust-tube on opposite sides of said piston to normally maintain an equal vacuum on each side of said piston, connections between said piston and said air-valve, a controlling-pipe normally in communication with said exhaust-tube through said cylinder, a valve for closing the open end of said tube and adapted to be opened by the insertion of a carrier to allow the entrance of atmospheric pressure into 125 said cylinder through said controlling-pipe 130

for operating said piston to open said air-valve to cause the passage of air through said transit-tube for the transmission of carriers.

5. In an apparatus of the character described, a transit-tube through which carriers are transmitted, an air-valve for controlling the passage of air through said transit-tube and normally closed, an exhaust-tube, mechanism under the control of said exhaust-tube and normally holding said air-valve closed, and means for admitting atmospheric pressure to said mechanism to open said air-valve upon the insertion of a carrier into said transit-tube to allow a passage of air through said transit-tube for the transmission of carriers.

6. In an apparatus of the character described, a transit-tube through which carriers are transmitted, an air-valve for controlling the passage of air through said transit-tube and normally closed, an exhaust-tube, mechanism under the control of said exhaust-tube and normally holding said air-valve closed, means for admitting atmospheric pressure to said mechanism to open said air-valve upon the insertion of a carrier into said transit-tube to allow a passage of air through said transit-tube for the transmission of carriers, and means for regulating the closing of said air-valve.

7. In an apparatus of the character described, a transit-tube through which carriers are transmitted, an air-valve controlling the passage of air through said tube and normally closed, an exhaust-tube, mechanism under the control of said exhaust-tube for operating said valve, mechanism operated by the carrier upon its insertion into the transit-tube for opening said air-valve, mechanism for closing said air-valve after the insertion of the carrier, and means for regulating the closing of said air-valve.

8. In an apparatus of the character described, transit-tubes through which carriers are transmitted in opposite directions, an air-valve controlling the passage of air through said transit-tubes and normally closed, an exhaust-tube in communication with both of said transit-tubes, mechanism under the control of said exhaust-tube and normally holding said air-valve closed, and means for admitting atmospheric pressure to said mechanism to open said air-valve upon the insertion of a carrier into said transit-tube to allow a passage of air through said transit-tubes for the transmission of carriers.

9. In an apparatus of the character described, transit-tubes through which carriers are transmitted in opposite directions, an air-valve controlling the passage of air through said transit-tubes and normally closed, an exhaust-tube in communication with both of said transit-tubes, mechanism under the control of said exhaust-tube and normally holding said air-valve closed, and means operated by a carrier inserted into either of said transit-tubes

for admitting atmospheric pressure to said mechanism to open said air-valve upon the insertion of a carrier into said transit-tube to allow a passage of air through said transit-tubes for the transmission of carriers.

10. In an apparatus of the character described, a transit-tube through which carriers are transmitted, an air-valve controlling the passage of air through said tube and normally closed, an exhaust-tube, and mechanism under the control of said exhaust-tube for opening said valve and allowing the passage of air through said transit-tube for the transmission of carriers.

11. In an apparatus of the character described, a transit-tube through which carriers are transmitted, an air-valve controlling the passage of air through said tube and normally closed, an exhaust-tube, and mechanism under the control of said exhaust-tube for automatically opening said valve and allowing the passage of air through said transit-tube for the transmission of carriers.

12. In an apparatus of the character described, a transit-tube through which the carriers are transmitted, an air-valve controlling the passage of air through said tube and normally closed, an exhaust-tube, and mechanism under the control of said exhaust-tube for automatically opening said valve and allowing the passage of air through said transit-tube for the transmission of carriers, and for automatically moving said air-valve into its closed position after the insertion of a carrier.

13. In an apparatus of the character described, a transit-tube through which carriers are transmitted, an air-valve controlling the passage of air through said tube and normally closed, an exhaust-tube, mechanism under the control of said exhaust-tube and operated by a carrier inserted into said tube for automatically opening said valve and allowing the passage of air through said transit-tube for the transmission of carriers.

14. In an apparatus of the character described, a transit-tube through which carriers are transmitted, an air-valve controlling the passage of air through said tube and normally closed, an exhaust-tube, and mechanism under the control of said exhaust-tube and operated by a carrier inserted into said tube for automatically opening said valve and allowing the passage of air through said transit-tube for the transmission of carriers, and for automatically moving said air-valve into its closed position after the insertion of a carrier.

15. In an apparatus of the character described, a transit-tube through which carriers are transmitted, an air-valve controlling the passage of air through said tube and normally closed, an exhaust-tube under the control of said air-valve, mechanism under the control of said exhaust-tube and normally holding said air-valve closed, and means for admitting atmospheric pressure to said mechanism to

open said air-valve to allow the passage of air through said transit-tube for the transmission of carriers.

16. In an apparatus of the character de-
5 scribed, a transit-tube through which carriers
are transmitted, an air-valve controlling the
passage of air through said tube and normally
closed, an exhaust-tube under the control of
said air-valve, mechanism under the control
10 of said exhaust-tube and normally holding
said air-valve closed, and means for admitting
atmospheric pressure to said mechanism to
open said air-valve to allow the passage of air
through said transit-tube for the transmission
15 of carriers and adapted to cut off atmospheric
pressure from said mechanism to allow said
mechanism to close said air-valve.

17. In an apparatus of the character de-
scribed, a transit-tube through which carriers
20 are transmitted, an air-valve controlling the

passage of air through said tube and normally
closed, an exhaust-tube under the control of
said air-valve, mechanism under the control
of said exhaust-tube and normally holding
25 said air-valve closed, and means for admitting
atmospheric pressure to said mechanism to au-
tomatically open said air-valve to allow the
passage of air through said transit-tube for
the transmission of carriers and adapted to cut
30 off atmospheric pressure from said mech-
anism to allow said mechanism to close said air-
valve automatically.

In testimony whereof I have signed my name
to this specification, in the presence of two sub-
scribing witnesses, this 23d day of August, 35

A. D. 1904.
